UNITED STATES PATENT OFFICE

2,512,115

PILE OINTMENT TUBE

Karl Senff, Detroit, Mich., assignor to R. P. Scherer Corporation, a corporation of Michigan

Application September 3, 1946, Serial No. 694,450

3 Claims. (Cl. 128—272)

1

This invention relates to improvements in fluid dispensing containers, tubes, capsules, or the like.

It relates particularly to an improved container for fluid composition, which container includes a compressible body portion and an elongate tubular neck portion communicating therewith and through which the fluid contents of the body portion are adapted to be ejected upon the collapse of such portion.

Heretofore such containers have been commonly formed wholly of gelatin or other similar flexible shell material. A conventional container of this character comprised a hollow compressible body provided with an elongate tubular neck through which the contents of the body could be expressed upon opening the outer end of the neck and squeezing the body to force the contents out through the neck.

One common commercial form of such container is the conventional gelatin pile ointment capsule wherein there is a hollow compressible body portion provided with an elongate tubular neck portion through which the ointment content of the body portion is ejected upon collapsing such hollow body.

It was common practice with this type of container, and it was true of the specific commercial type of container above mentioned, for the elongate tubular neck portion to be designed for insertion into an orifice of the human body for the discharge of the contents of the container thereinto. In the pile ointment container hereinabove referred to the body portion and the neck portion were both formed of the same gelatin composition material. If the gelatin sheet material used in the formation of the capsule were sufficiently soft and flexible to permit easy collapse of the body between the fingers, the long narrow neck portion of the container was so soft and flexible that as a consequence it was frequently difficult to insert such neck into the intended orifice without the neck bending or doubling over. If the gelatin sheet material used in the formation of the capsule were sufficiently rigid to provide a neck sufficiently stiff as to insure easy insertion thereof into the intended orifice, the shell of the body of the capsule was so rigid as to render its collapse difficult.

An object of this invention is to provide a dispensing container of the character described

2

which has a soft, flexible, readily compressible, hollow body portion and also has an elongate tubular neck portion through which the fluid contents of the body may be expressed upon compression of the body, and the wall of which neck portion is so rigid and stiff that the neck can be readily inserted against resistance into the intended orifice without undesirable bending or flexing of the neck portion.

10 Another object is to provide a container characterized as above described, the wall of which container is formed throughout of gelatin composition, and wherein the hollow body portion of the capsule is so soft and flexible that it can be

15 easily collapsed between the fingers of a user to expel the contents thereof, and wherein the long tubular neck portion of the capsule is so stiff that it can be readily inserted against resistance into an orifice.

20 A further object is to provide a container having a body portion and a neck portion and which container is so formed that a portion of its wall which extends lengthwise throughout at least the length of the neck is relatively rigid and another portion of its wall which extends lengthwise throughout the body is relatively soft and compressible so that the body may be collapsed to express the contents thereof through the neck.

25 In one specific embodiment the wall of the container consists of two opposed complementary longitudinally extending side wall sections sealed together along a seam line extending longitudinally of the container. Both of these side walls are formed of gelatin composition, but one side

30 wall is formed of gelatin sheet material which is relatively flexible and the other side wall is formed of gelatin sheet material which is relatively stiff. The stiff side wall rigidifies the neck portion of the capsule so that the neck may be readily inserted into an orifice against resistance; the soft side wall provides a flexible body wall which permits collapse of the body for expressing its contents.

35 My improved container is simple, inexpensive and easily fabricated according to approved commercial processes. Its shell is preferably formed entirely of gelatin composition or other suitable plastic sheet material. The container, and particularly the discharge neck portion thereof, is sufficiently rigid along its longitudinal axis to

40

serve the purpose intended and the hollow body wall portion is sufficiently flexible to be easily collapsed.

Other objects, advantages and meritorious features will more fully appear from the following description, appended claims and accompanying drawing wherein:

Figure 1 is an elevation of an improved dispensing container or a capsule embodying the invention.

Figure 2 is an elevation of the structure shown in Figure 1 showing the two halves of the container separated from each other, and

Figure 3 is a vertical sectional view taken on the line 3—3 of Figure 1.

This improved container wherein the body portion is so formed as to exhibit sufficient flexibility to permit of ready collapse thereof sufficient to express the fluid contents of the body and wherein the neck portion is so formed as to exhibit sufficient rigidity to facilitate an insertion of such neck into an orifice against resistance, may preferably be constructed by providing two complementary wall portions which extend lengthwise of the container and are sealed together along a seam line and one of which wall portions is relatively rigid and the other of which wall portions is relatively flexible. Preferably the entire wall of the container may be formed of some suitable plastic material such as gelatin composition. One wall portion, indicated as 10, might be formed of relatively soft and flexible gelatin sheet material; the other wall portion 12 might be formed of relatively stiff and rigid gelatin sheet material.

These two complementary longitudinal halves are sealed together along a seam line 14 so as to provide a unitary hermetically sealed container or capsule. The relatively soft and flexible shell portion renders that part of the capsule body sufficiently flexible to permit collapse of the body to express the fluid contents of the body. The relatively rigid shell portion renders that part of the neck sufficiently rigid to permit insertion of the neck into an opening against resistance. These two half-portions of the shell may be differently colored if desired.

It is common practice to form capsules of this kind from two gelatin sheets between a pair of complementary dies, one-half of each capsule being formed from each sheet. Due to this method of manufacture it is entirely practicable to provide one-half of the capsule of relatively stiff sheet material and the other half of the capsule of relatively flexible sheet material.

The art well understands how to increase the flexibility or rigidity of gelatin sheets. The degree of flexibility of the two sides of the finished tubes is determined by the relative amounts of gelatin on the one hand and glycerine or sorbitol syrup on the other hand. As the percentage of glycerine or sorbitol syrup in the gelatin composition is increased at the expense of the gelatin the flexibility of the gelatin sheet is increased. The following examples are illustrative of suitable formulas:

Example I

	Rigid Side	Soft Side
Gelatin.....	Per cent	Per cent
Water.....	82	60
Glycerine.....	8	10
	10	30

Example II

	Rigid Side	Soft Side
5 Gelatin.....	Per cent	Per cent
Water.....	79	55
Glycerine.....	8.999834	10.99983
Titanium Dioxide.....	12	24
Dyes:	.0001	.0001
Red #1.....	.00001	.00002
Yellow #5.....	.000005	
Blue #1.....	.000001	
10		

Example III

	Rigid Side	Soft Side
15		
Gelatin.....	Per Cent	Per cent
Water.....	67	42
85% Sorbitol Syrup.....	13	18
	20	40

Example No. 2 is one in which the two halves are of different colors. The examples are merely illustrative. In each, the formula for the two sides is appropriate to obtain the desired result.

What I claim is:

1. A fluid dispensing capsule of the pile ointment type comprising a hollow body portion provided with a communicating elongate tubular neck portion, the wall of said container throughout the body portion and the neck portion being formed of opposed complementary longitudinal side wall sections of plastic material sealed together along a longitudinal seam line, one side wall section being formed of plastic material of substantially greater rigidity than the other.
2. A fluid dispensing capsule of the pile ointment type comprising a hollow body portion provided with a communicating elongate tubular neck portion, the wall of said container consisting of opposed complementary longitudinal side wall sections of plastic material each being integral throughout the body portion and the neck portion, said sections being sealed together along a longitudinal seam line extending throughout the body portion and the neck portion, one side wall section being formed of material sufficiently flexible throughout the body portion of the container to permit of collapse thereof and the other side wall section being formed of material sufficiently rigid throughout the neck portion of the container to prevent bending upon resisted insertion lengthwise into an orifice of the body.
3. A fluid dispensing capsule of the pile ointment type comprising a hollow body portion provided with a communicating elongate tubular neck portion, said container consisting of two opposed complementary longitudinal side wall sections of gelatin composition sealed together along a longitudinal seam line extending throughout the body portion and the neck portion, one side wall section being formed of relatively stiff and rigid gelatin sheet material and the other side wall section being formed of relatively soft and flexible gelatin sheet material.
